UNITED STATES PATENT OFFICE

122,710

DESIGN FOR A COMBINED LAMP AND
CIGARETTE CONTAINER

Florence May, Atlanta, Ga.

Application November 24, 1939, Serial No. 88,465

Term of patent 7 years

To all whom it may concern:

Be it known that I, Florence May, a citizen of the United States, residing at Atlanta, in the county of Fulton and State of Georgia, have invented a new, original, and ornamental Design for a Combined Lamp and Cigarette Container, of which the following is a specification, reference being had to the accompanying drawing, forming a part thereof.

The figure is a perspective view of the combined lamp and cigarette container showing my new design.

I claim:

The ornamental design for a combined lamp and cigarette container, substantially as shown.

FLORENCE MAY.
